CLAIM

The ornamental design for an attachable garden nozzle light,
as shown and described.

DESCRIPTION

FIG. 1 is a perspective view of the present invention,
showing the new design of the attachable garden nozzle
light;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line disclosure forms no part of the claimed
design.
